ATTORNEY.

UNITED STATES PATENT OFFICE

97,991

DESIGN FOR A GAME DEVICE

Isaac M. Dunwoody, Denver, Colo.

Application September 3, 1935, Serial No. 58,404

Term of patent 14 years

To all whom it may concern:

Be it known that I, Isaac M. Dunwoody, a citizen of the United States of America, residing at Denver, in the county of Denver and State of Colorado, have invented a new, original, and ornamental Design for a Game Device, of which the following is a specification, reference being had to the accompanying drawing, forming part thereof.

In the drawing:—

Fig. 1 is a front elevation of a game device showing my new design;

Fig. 2 is a top plan view thereof.

I claim:

The ornamental design for a game device as shown.

ISAAC M. DUNWOODY.
